United States Patent

Des. 235,888
Patented July 15, 1975

235,888

ARMY PLAQUE

Lewis J. King, Jr., Arlington, Va., assignor to The United States of America as represented by the Secretary of the Army

Filed June 25, 1974, Ser. No. 482,971

Term of patent 14 years

Int. Cl. D11—02

U.S. Cl. D29—23 A

FIG. 2

FIG. 1

FIG. 1 is front elevational view of an army plaque showing my new design, contrasting color being depicted schematically; and

FIG. 2 is an end elevation thereof.

The rear of my new design for a plaque is plain and unornamented.

The design described herein may be reproduced and used by or for the Government for governmental purposes without the payment to me of any royalty thereon.

I claim:

The ornamental design for an army plaque, as shown and described.
